UNITED STATES PATENT OFFICE.

TALBOT C. DEXTER, OF PEARL RIVER, NEW YORK.

PAPER-FEEDING MACHINE.

Application filed July 29, 1925. Serial No. 46,700.

This invention relates to paper feeding machines and more particularly to that class of paper feeding machines wherein the paper feeding cycle of operation is pneumatically controlled.

Among the objects of the present invention is to produce pneumatically controlled devices which will lift a sheet of paper from a pile of paper and by such action cause said devices to advance the sheet of paper a definite distance.

Another object of the invention is to provide a latch whereby the forward movement of the advancing mechanism and the accompanying advance of the sheet of paper is prevented until the forward edge of the sheet of paper is completely lifted from the remaining sheets of the pile of paper.

Another object is to provide suction controlled advancing mechanism which will operate to lift a single sheet of paper from a pile of paper preliminary to the advancing movement of said sheet of paper after there has been only a minimum amount of separation of said sheets of paper from the pile of paper by a comb-wheel.

Another object is to provide mechanism which will cause a sheet of paper to adhere to it so that it may be advanced, and, at the same time, to cause advancement of said sheet of paper by auxiliary mechanism to cease by rendering said auxiliary mechanism ineffective when the sheet of paper has come into contact with said advancing mechanism.

Another object is to provide means whereby the amount of forward movement of the advancing mechanism and accompanying forward movement of a sheet of paper, may be terminated after the paper has been advanced a predetermined distance, and whereby the operation of auxiliary advancing mechanism may be automatically resumed to be operative to cause separation and preliminary advance of the next succeeding sheet.

With these and incidental objects in view, the invention consists of certain novel features of construction and combinations of parts, the essential elements of which are set forth in the appended claims and a preferred form of embodiment of which is de-

scribed hereinafter with reference to the drawings which accompany and form part of the specification.

Fig. 1 is an elevation of the right side of 55 the paper feeding machine.

Fig. 2 is an elevation as viewed from the front of the machine, with parts broken away.

Fig. 3 is a longitudinal view of the paper 60 feeding mechanisms, partly in section, taken on line 3—3 of Fig. 5.

Fig. 4 is a view similar to Fig. 3, with the parts in a position of the most advanced 65 position of the automatic paper advancing mechanism.

Fig. 5 is a plan view of the paper feeding machine illustrating one automatic feeding unit.

Fig. 6 is a detail of the various cams and 70 the coacting rollers.

Fig. 7 is a perspective view of the paper advancing head and its guiding rails.

Referring to the drawings for a more detailed description of the machine, the paper feeding mechanism is supported on a frame comprising left and right members 10 and 11, the left frame being supported by two columns 12—13, and the right frame being supported by two similar columns 14—15. 75 The columns 12—13, extend upwardly from a beam 16 and columns 14—15 extend upwardly from a beam 17, the beams being maintained in spaced relation by rods 18—19. Frames 10—11 also are maintained in 80 spaced relation by three rods 20, 21 and 22.

In the present form, power for driving the various shafts and mechanical units of the machine is derived through the medium of roller shaft 23 journaled in the forward 85 ends of frames 10 and 11. The right hand end of this shaft carries a sprocket wheel 24 which may be connected by a chain to a motor or any other source of power. This shaft will rotate continuously and cause the 90 rotary parts of the machine to function continually, but the pneumatic devices for advancing a sheet of paper are automatically controlled by the presence and actual 95 feeding operation of the sheet of paper 100 being fed.

To shaft 23 is secured a pinion 25 which

meshes with an idler gear 26 loose on stub shaft 27. 28 is the cam shaft to the right hand end of which is secured a gear 29 which meshes with idler gear 26. Another 5 idler gear 30 is loosely mounted on stub shaft 31 extending from side frame 11 and it engages gear 29 on shaft 28 and drives shaft 32 through gear 33.

The paper feeding unit, about to be described, receives its operating power through cam shaft 28 and shaft 32. For the purpose of simplifying the disclosure, only one of these paper feeding units has been illustrated, but it is to be understood that where 10 the occasion makes it desirable a plurality of similar units may be employed, as for example, where, in large machines, wide sheets of paper are to be fed. The operating parts of each paper feeding unit are 15 mounted on a single frame member 34 which is supported by rods 20 and 21 and may be positioned anywhere between side frames 10 and 11. Should only one paper feeding unit be used it would be advantageously 20 positioned midway between frames 10 and 11 and gear 35 would be secured to shaft 32 so as to continually mesh with gear 36 loose on rock shaft 37 extending from frame 34. Also loosely mounted on rock shaft 37 is an 25 arm 38 having journaled in its forward end shaft 39 to which is secured comb wheel 40. Arm 38 also carries a stub shaft 41 and an idler gear 42 which engages gear 36 and gear 43 on shaft 39. Comb-wheel 40 will 30 be rotated in a clockwise direction by the gearing just described and its effectiveness to preliminarily advance a sheet of paper is dependent upon whether it is in contact 35 with the pile of paper or whether it is removed from contact by mechanism to be described hereinafter.

To frame 34 is bolted a rail 44 on which a block 45 may be slid forwardly when a sheet of paper is to be advanced. The block 45 carries a cylinder 46 closed at its upper end by a cap 47 through which a passage is bored. Fitted to slide within the cylinder is a piston comprising a head 48 and a tube 49 which slides in sleeve 50 extending from the cylinder. To the lower end of tube 49 is secured a boss 51 having an arm 52 which carries a roller 53. Pinned to the same pin as roller 53 is a link 54 having an elongated slot in which a stud on arm 55 engages. 50 Arm 55 is pivoted on block 45 and its rear end is hooked so as to engage stud 56 on rail 44 when the piston is in its home position as illustrated in Fig. 3. A plate 57 having perforations therein is fastened beneath boss 51.

A projection 58 of the cylinder cap 47 forms a suitable surface to which is fitted a flexible hose 59 which connects cylinder 46 with cylinder 60 by means of nozzle 61. 55 Tapped into the rear end of cylinder 60 is

a hose 62 which is connected to a vacuum pump, not shown, which continually tends to draw air through the perforations in plate 57, tube 49, cylinder 46, flexible hose 59, nozzle 61, and cylinder 60.

70

When a sheet of paper is advanced from the pile of paper by the comb-wheel 40, the air entering tube 49 through the perforations in plate 57 creates a suction which lifts the uppermost sheet toward the plate. This action causes the sheet of paper to cover and close the perforations thereby creating a vacuum pressure on the connecting passageways above described which serves to firmly maintain the sheet of paper against the under side of the plate. The reduced pressure in cylinder 46 will cause piston tube 49 to be raised thus causing the lower end of the slot in link 54 to contact the stud on arm 55 and raise the arm out of latching relation with stud 56.

75

Meanwhile, the vacuum pressure created in cylinder 60 has operated to draw piston 63 rearwardly together with connecting rod 64 and crank 65 which is loosely mounted on rock shaft 37. Crank 65 has integral therewith a finger 66 which underlies a projection 67 extending laterally from arm 38, and the clockwise or rearward movement of crank 65 causes arm 38 to be rotated clockwise thus raising the comb-wheel from contact with the pile of paper.

80

The outer end of rock shaft 37 has pinned thereto a hub 68 from which extends a lug 69 which underlies projection 67 extending laterally from arm 38. Extending upwardly from hub 68 is a crank 70 that is connected by a pin 71 to a pitman 72 having a bifurcation at its forward end which engages cam shaft 28 and serves to guide the pitman 105 in its translating movement. Pitman 72 carries a roller 73 which bears against the periphery of cam 74 on shaft 28. Shortly after comb wheel 40 has been raised by the rearward motion of piston 63, the high part 110 of cam 74 passes beneath roller 73 and causes pitman 72 to be moved rearwardly. This action causes hub 68 to be rotated clockwise and this new position of lug 69 directly beneath the new position of projection 67 on 115 arm 38 insures the maintenance of arm 38 in its raised position. It will be evident from the foregoing description that should piston 63 fail to operate to raise the comb wheel, the comb wheel would be raised positively by the coaction of cam 74 against roller 73 on pitman 72.

120

With the piston tube 49 raised, as above described, to its highest position arm 55 will no longer engage stud 56 and block 45 will 125 be free to be slid forwardly on rail 44. Cam 75 on cam shaft 28 thereafter controls the reciprocation of block 45. Journaled in side frame 10 and frame 34 is a short shaft 76 to which is secured arm 77 extending rear- 130

wardly and carrying a roller 78 which contacts with the periphery of cam 75. Downwardly extending arm 79 also is secured to shaft 76 and it has a link 80 at its lower end which is pivotally connected with block 45. Near to the upper end of arm 79 is pinned a rod 81, the rear end of which slides through a stud 82 projecting from the left side of frame 34. A spring 83 is compressed 5 between this stud and a collar 84 on the rod and when the high part of cam 75 has passed from beneath roller 78, the spring will urge arms 77 and 79 in a clockwise direction and move block 45 to the position illustrated in 10 Fig. 4.

When more than one paper feeding unit is to be used only one cam 75 and arm 77 is necessary, but it would then be necessary to have as many arms 79, fixed to shaft 76, 20 as there are units, and shaft 76 could be longer for this purpose. The lower ends of the arms 79 each would be connected to each of the blocks 45 as above described, and when the high part of cam 75 would pass 25 from beneath roller 78 all of the blocks would be urged forwardly by the respective springs 83. The forward movement of all of the blocks would be delayed, however, should any one of the pistons 49 fail to completely rise, since, in that case, its latch 55 30 would remain hooked to stud 56. Should the failure of the piston to completely rise be due to a lack of complete closure of the holes in the respective plates 57, the comb 35 wheels would continue to urge the paper forward, and as soon as each set of holes in each plate was covered all of the pistons would rise to the position illustrated in Fig. 4 and each would be equally effective to hold and 40 advance the paper.

In this position, the high part of cam 85 will pass from beneath roller 86 and allow arm 87, loose on shaft 76, to rotate clockwise thereby removing finger 88 from restricting relation with plunger 89. This plunger is mounted in a boss 90 extending from frame member 34 and it is continually urged upwardly by a compression spring 91 fitting into a recess in the boss and contacting a collar 92 fast to the plunger. The upward movement of the plunger is limited by a collar 93 which bears against the under side of boss 90 when the spring is allowed to raise the plunger as above described. 55

To the lower end of plunger 89 is fastened a track 94 against which a roller 95 on the forward end of lever 96 travels. The track is maintained in its proper position by two pins 97-97, which are fastened thereto and slide in holes in boss 90. Lever 96 is pivoted on a bracket carried by block 45 and roller 95 is continually urged in a clockwise direction by spring 98. To the rear end of lever 96 is a valve-cap 99 which 60 covers a port 100 in cylinder 46 when the

parts are in the positions illustrated in Fig. 3.

However, after the block has been moved forward and cam 85 has allowed arm 87 to drop and plunger 89 and track 94 to rise, Fig. 4, spring 98 will function to rotate lever 96 and remove valve-cap 99 from port 100. This action will cause a release of the vacuum pressure in cylinder 46, and the sheet of paper will no longer be held to the under surface of plate 57. Piston tube 49 will not 75 descend for roller 53 is above bar 101 and it will maintain the piston tube and its associated parts in their raised position until the block has been moved to its home position where the roller will leave the end 1021 80 of the bar 101 and allow the piston tube to drop to the position shown in Fig. 3.

When the vacuum pressure is broken in cylinder 60, the restraining effect of crank 65 on arm 38 will cease but the comb wheel 85 will not drop until the high portion of cam 74 has passed from beneath roller 73 on pitman 72.

102 is a rock shaft journaled in side frames 10 and 11 and it has pinned thereto two arms 103 each carrying a friction roller 104 at its end. These rollers are situated directly above feed roll 105 on shaft 23 and normally are restrained from contact therewith by a cam 106 at the right end of shaft 28. This cam controls the rise and fall of rollers 104 through a roller 107 which is carried by the rear end of arm 108, pinned to rock shaft 102.

While the block is in its forward position over shaft 23 and after the valve-cap 99 has been removed from port 100, cam 106 will have been rotated enough to allow friction rollers 104 to descend upon the sheet of paper that has been advanced by the block 105 and released from the under side of plate 57.

The sheet of paper will then be rapidly advanced by the feed roll 105 and discharged from the machine. Further rotation of shaft 28 will cause cam 106 to raise arm 108, rock shaft 102, and raise friction rollers 104. Cam 75 will then operate to swing arm 77, shaft 76, and arm 79 counterclockwise against the action of spring 83 to restore block 45 to home position; and just 115 about when the block has arrived at its home position, cam 85 will raise arm 87 and cause finger 88 to depress plunger 89 and track 94 so as to restore valve cap 99 in its position over port 100, Fig. 3. Cam 74 120 will now allow pitman 72 to move forwardly and comb wheel 40 will descend to the surface sheet of the pile of paper and proceed by its revolving action to comb the paper towards the holes in plate 57.

A tube 109 extends across the front of the machine and air is pumped therethrough from conduit 110. A valve 111 is tapped into the middle of this tube and a flexible hose 112 connects the valve with a nozzle 113 130

which is vertically disposed immediately beneath the holes in plate 57 when block 45 is in its home position, Fig. 3. The flow of air from this nozzle raises the foremost and top sheet from the uppermost sheets that are being advanced by the comb wheel so as to lift it against plate 57 in order that it will be caused to adhere thereto by the suction through the holes in the plate. The use of the nozzle in this manner allows rapid operation of the machine, as it is only necessary that the top sheet be advanced a very slight distance by the comb wheel ahead of the sheets immediately thereunder before the suction plate can grasp it, so to speak, and automatically operate to lift the sheet.

As the paper is advanced by the forward movement of block 45 its own forward movement will be assisted by its passage over a feed roll 114 mounted on shaft 115 which is journaled in frames 10 and 11. Shaft 115 is driven by shaft 23 which carries at its left end a gear 116 which is in engagement with an idler gear 117, loosely mounted on tube 109. This gear meshes with gear 118 fast on shaft 115 and completes the driving connection between shafts 23 and 115.

In order to clarify the description of the machine, the timing of the various cam actions in relation to one another has been set forth, but I desire it to be understood that the timing relations can be varied to suit the operator of the machine and to accommodate the machine to feed the different grades of paper for which it is to be used.

In this type of machine the paper is stacked upon a table 119 and this table is raised automatically by mechanisms designed for this purpose and which are well known in the art. It is only necessary that the surface of the pile of paper be maintained within contacting distance of the comb wheel.

While the form of mechanism herein shown and described is admirably adapted to fulfill the objects primarily stated, it is to be understood that it is not intended to confine the invention to the one form of embodiment herein disclosed, for it is susceptible of embodiment in various forms all coming within the scope of the appended claims.

What I claim is—

1. A paper feeding device comprising a reciprocatory head having a suction chamber and ports for causing paper to adhere thereto, means for reciprocating said head to advance adhering paper, a comb wheel for feeding a sheet of paper toward said reciprocatory head, and means for automatically discontinuing the feeding operation of said comb wheel when a sheet of paper is caused to adhere to said reciprocatory head.
2. A paper feeding device comprising a movable head having a suction chamber and

ports for causing paper to adhere thereto, means to advance a sheet of paper in proximity to said head, means to cause the cessation of operation of said means concomitantly with the adherence of said sheet of paper to said head, and driving mechanism for actuating the head to advance the paper after such cessation.

3. A paper feeding device comprising a movable hollow head having ports for causing paper to adhere thereto, means to advance a sheet of paper in proximity to said ports, connections between said hollow head and said means for rendering said means ineffective to advance paper when a sheet of paper is held by said hollow head, and mechanism for actuating the head to carry the adhering paper forward.

4. A paper feeding device comprising a movable hollow head having ports for causing paper to adhere thereto, means to advance a sheet of paper in proximity to said ports, connections between said hollow head and said means for automatically rendering said means ineffective to advance paper concomitantly with the picking up of a sheet of paper by said hollow head, and devices for operating the head to advance the paper fed by said means.

5. A paper feeding device comprising a movable hollow head having ports for causing paper to adhere thereto, means to separate the top sheets of paper from a pile of paper, means to automatically discontinue the effective operation of said first mentioned means when a sheet of paper is picked up by the suction at the ports of said hollow head, and means for moving said head to advance paper fed by said means.

6. A paper feeding device comprising a tube having a suction chamber therein and perforations adapted to draw a sheet of paper thereto and means for operating said head to advance the paper, a comb wheel for advancing sheets of paper toward said perforations, and means for discontinuing the effectiveness of said comb wheel when the most advanced sheet of paper is picked up by said tube.

7. A paper feeding device comprising a tube having a suction chamber therein and perforations adapted to draw a sheet of paper thereto, a comb wheel to separate the uppermost sheets of a pile of paper, means to withdraw said comb wheel from contact with said pile of paper when a sheet of paper is caused to adhere to said tube, and means for thereafter actuating the suction device to advance and release the paper.

8. A paper feeding device comprising a tube and perforations through which air may be drawn so as to cause paper to adhere thereto, a comb wheel for separating the sheets of paper from a pile of paper and advancing the uppermost sheet toward said

tube, and means for thereafter bodily moving the suction device to carry the paper away from the comb wheel.

9. A paper feeding device comprising a tube and perforations through which air may be drawn so as to cause paper to adhere thereto, a comb wheel for separating the sheets of paper from a pile of paper, automatic means for withdrawing said comb wheel from said pile of paper when the foremost sheet of paper is picked up by said tube, and means for thereafter moving said tube to carry forward the adhering paper and for releasing the suction to free said paper after it is fed.

10. A paper feeding device comprising a bodily movable suction cylinder having a piston head therein, a tube attached to said piston head, a plate having perforations therein covering the external end of said tube, a comb wheel for advancing paper toward said plate, pneumatically controlled means to terminate the effectiveness of said comb wheel when a sheet of paper is held against the perforations in said plate, and devices for bodily moving the cylinder to carry the paper forward after the comb wheel becomes ineffective.

11. A paper feeding device comprising a bodily movable suction cylinder having a piston head therein, a tube attached to said piston head, a plate having perforations therein covering the external end of said tube, a comb wheel for advancing paper toward said plate, means connected to said comb wheel for removing it from coacting relation with said paper, said means being adapted to automatically operate when a sheet of paper is advanced opposite said perforations, and means for thereafter moving the suction cylinder to feed the paper and then release the suction.

12. A paper feeding device comprising a block, a cylinder mounted on said block, a rail for guiding said block in a translatory movement, a hollow piston adapted to reciprocate in said cylinder, and a plate having perforations and moving with the piston, said hollow piston being adapted to be drawn into said cylinder when the perforations in said plate are covered by a sheet of paper.

13. A paper feeding device comprising a block, a cylinder mounted on said block, a rail for guiding said block in a translatory movement, a hollow piston in said cylinder, a conduit for drawing air from said cylinder, said hollow piston being adapted to cause a sheet of paper to adhere thereto and close its open end, whereby said hollow piston is caused to rise and lift said sheet of paper, and a latch controlled by the piston for preventing translatory movement of the block until the paper has been lifted the required distance.

14. A paper feeding device comprising a block, a cylinder mounted on said block, a rail for guiding said block in a translatory movement, a hollow piston in said cylinder, a comb wheel for advancing paper toward said hollow piston, a second cylinder, a piston in said second cylinder connected to said comb wheel, a tube communicating with said two cylinders for drawing air therethrough to actuate said pistons when a sheet of paper closes the opening in said hollow piston.

15. A paper feeding device comprising a block, a cylinder mounted on said block, a rail for guiding said block in a translatory movement, a hollow piston in said cylinder, a passageway whereby air may be evacuated from said cylinder, a hook on said block for maintaining it in a definite position on said rail, and means to unlatch said hook when said hollow piston is actuated.

16. A paper feeding device comprising a block, a cylinder mounted on said block, a rail for guiding said block in a translatory movement, a hollow piston in said cylinder, a passageway whereby air may be evacuated from said cylinder, an opening in said hollow piston adapted to be closed by a sheet of paper and thereby cause said piston to be actuated, means to actuate said block along said rail and advance said sheet of paper, a latch controlling movements of the aforesaid block and operating connections for the latch actuated by the piston.

17. A paper feeding device comprising a block, a cylinder mounted on said block, a rail for guiding said block in a translatory movement, a hollow piston in said cylinder, a passageway whereby air may be evacuated from said cylinder, means controlled by the sheets of paper being fed for causing said piston to be actuated, a latch for locking said block in a definite position on said rail, and means to release said latch when said piston is actuated.

18. A paper feeding device comprising a block, a cylinder mounted on said block, a rail for guiding said block in a translatory movement, a hollow piston in said cylinder, a passageway whereby air may be evacuated from said cylinder, means controlled by each sheet of paper fed for actuating the piston, a latch for locking said block in a definite position on said rail, means to release said latch when said piston is completely actuated, and means to actuate said block along said rail to advance said sheet of paper.

19. A paper feeding device comprising a block, a cylinder mounted on said block, a rail for guiding said block in a translatory movement, a hollow piston in said cylinder, a passageway whereby air may be evacuated from said cylinder, means controlled by passing sheets of paper for actuating the piston, a valve-cap for covering a port in said cylinder, and means to remove said

valve-cap from said port to cause the release of said piston.

20. A paper feeding device comprising a block, a cylinder mounted on said block, a rail for guiding said block in a translatory movement, a hollow piston in said cylinder, a passageway whereby air may be evacuated from said cylinder, means controlled by the passing sheets of paper for actuating the piston, a valve-cap for covering a port in said cylinder, means to advance said block on said rail, and means to displace said valve-cap from said port after said block has been advanced a predetermined distance.

15. 21. A paper feeding device comprising a block adapted to be reciprocated upon a rail, said block carrying a chamber having a port therein, a valve-cap for normally covering said port, connections for evacuating the air 20 from said chamber, a hollow piston whereby air may be drawn into said chamber, means whereby sheets of paper are successively fed towards the open end of said hollow piston, said sheets of paper serving to close said 25 open end and cause said hollow piston to hold and raise the sheets of paper, means for advancing said block and a sheet of paper, and means for operating said valve-cap to uncover said port and cause the release of 30 said paper.

22. A paper feeding device comprising a block adapted to be reciprocated upon a rail, said block carrying a chamber having a port therein, a valve-cap for normally covering 25 said port, connections for evacuating the air from said chamber, a hollow piston whereby air may be drawn into said chamber, means whereby sheets of paper are successively fed towards the open end of said 40 hollow piston, said sheets of paper serving to close said open end and cause said hollow piston to hold and raise the sheets of paper, means for advancing said block and a sheet of paper, and means for removing said 45 valve-cap from said port to cause the release of said sheet of paper and the discontinuance of the effective operation of said first named means.

23. In a paper feeding machine, the combination of a suction cylinder, a hollow piston adapted to be drawn therein by suction, a plate having ports over the end of said hollow piston, a nozzle for directing a current of air towards said ports, and means to 55 feed the uppermost sheets of a pile of paper toward said nozzle whereby the uppermost sheet is lifted against said plate by the current of air.

24. In a paper feeding machine, the combination of a suction cylinder, a hollow piston adapted to be drawn therein by suction, a plate having ports over the end of said hollow piston, a comb wheel for brushing the uppermost sheets of paper toward said 65 ports in said plate, and a nozzle for direct-

ing a current of air to raise the front end of the uppermost sheet of paper into contact with said plate.

25. In a paper feeding machine, the combination of a suction cylinder, a hollow piston adapted to be drawn therein by suction, a plate having ports over the end of said hollow piston, a comb wheel for brushing the uppermost sheets of paper toward said ports in said plate, a second cylinder, means in said second cylinder connected to said comb wheel, a passageway connecting said cylinders, and a nozzle for lifting a sheet of paper to cover the ports in said plate whereby the suction created operates to draw the hollow piston into said first named cylinder and simultaneously terminate the brushing operation of said comb wheel.

26. A paper feeding apparatus comprising a continuously driven comb wheel and means for intermittently moving it into and out of feeding contact with the successive sheets of paper which are to be fed, mechanism comprising a suction device operable to lift and feed onward the paper fed by the comb wheel, and devices pneumatically controlled by the suction device for effecting the intermittent movements of the comb wheel.

27. A paper feeding apparatus including a first feeding mechanism comprising a comb wheel, devices for intermittently operating the comb wheel to feed sheets of paper part of the way off of a stack, a second feeding mechanism comprising a suction device for lifting the sheets fed by the comb wheel and advancing them to complete the feeding movement of the sheets, and devices controlled by the suction device for regulating the sequential operations of the first and second feeding mechanisms.

28. A paper feeding apparatus including a first feeding mechanism comprising a comb wheel, devices for operating the comb wheel to feed sheets of paper successively part of the way off of a stack, a second feeding mechanism comprising a suction device for lifting the sheets fed by the comb wheel and advancing them to complete the feeding movement of the sheets and devices comprising a latch controlled by the suction device for effecting operations of the second feeding mechanism in a timed relation with reference to the feeding of the comb wheel.

29. A paper feeding apparatus including a first feeding mechanism comprising a comb wheel, devices for operating the comb wheel to feed sheets of paper successively part of the way off of a stack, a second feeding mechanism comprising a suction device for engaging the sheets fed by the comb wheel and advancing them to effect a further feeding movement of the sheets, and devices comprising a latch controlled by the suction device for preventing operation of the second

feeding mechanism until a sheet has been fed thereto by the first feeding mechanism.

30. A paper feeding apparatus including a comb wheel and means for operating it to feed sheets of paper from a stack, a second feeding mechanism rendered effective to feed the paper by engagement therewith of sheets fed by the comb wheel, and means whereby

initial operation of the second feeding mechanism will render the comb wheel ineffective to feed paper until the feeding operation of the second feeding mechanism is completed. ¹⁰

In testimony whereof I hereto affix my signature.

TALBOT C. DEXTER.
